UNITED STATES PATENT OFFICE

LOUIS AUSTER, OF NEW YORK, N. Y.

BATHING SANDAL

Application filed March 28, 1929, Serial No. 350,542, and in Canada September 22, 1928.

The present invention relates to bathing sandals and to a method of manufacturing the same, and consists in the steps of procedure in making and combinations and arrangements of elements forming the article as hereinafter described and particularly set forth in the accompanying claims.

The type of sandal shown herein is proposed as an improvement or modification of 10 that style or construction of sandal and method of manufacturing the same disclosed in my co-pending application for U. S. Patent entitled "Bathing sandal and method of producing same", Serial No. 300,618, and filed 15 August 20, 1928.

Present known bathing slippers are characterized in that they are made in several pieces united together, as by cementing, in the so-called curing process with the result 20 that there is no uniformity in the strength of the article and consequently the different portions of the slipper frequently come apart due to insecure union along the seams. To avoid this defect it is here proposed to produce a bathing sandal or slipper in one piece 25 and in a single and unbroken process of moulding.

Present made slippers are furthermore bulky and require individual packing boxes 30 with the natural result that considerable space is needed for keeping on hand a reasonable supply or stock on the part of the dealers, and this in turn has resulted in many dealers refusing to carry a line of bathing slippers 35 for ready sale to the trade. There is a further disadvantage in that the present day bathing slippers in addition to being bulky are tending to run in styles, and this obviously further aggravates the disadvantage 40 above referred to.

From the standpoint of the wearer the present known bathing slippers are not only heavy in themselves but they collect and retain water around the wearer's feet and therefore 45 by considerably retard one's progress in swimming. As a consequence of the slippers becoming too heavy they are frequently forced off while swimming, and lost, and for this reason many bathers prefer to remove 50 the slippers before entering the water.

Another objection is that if the slipper be worn for some time while out of the water the wearer's feet being entirely encased in rubber become excessively hot and perspire, thereby causing great discomfort.

To overcome these disadvantages it is proposed to provide a bathing sandal or slipper that is moulded in preferably one piece and consequently is lighter, cheaper, stronger, and less bulky than the kind now used. Secondly, to provide a sandal which during wear will permit free circulation of air to every part of the foot while on land and effectively shed water when swimming. And thirdly, to provide a sandal which may be easily put on and removed, readily adjustable to the foot, and neat and attractive in appearance.

A further advantage—and an essential one—is to produce a bathing slipper which with its foot attaching appendages may be manufactured, shipped, and stored in a substantial lay-flat condition all to the end of economy in cost of production, conservation of space both for the dealer and owner, permitting a full line of articles being easily carried by a dealer with the minimum space in his sales room, in like manner requiring minimum space in transportation, and which because of the personal advantages aforesaid will commend the article to the wearers.

The invention is shown by way of illustration in the accompanying drawings, wherein:

Figure 1 is a perspective view of the sandal.

Figure 2 a perspective view showing the sandal in its lay-flat condition as coming from the mould.

Figures 3, 4 and 5 illustrate the selective application of the sandal to the foot in the "Grecian", "Swimmer" or "Roman" styles, respectively.

Figure 6 is a perspective view of a modified form of sandal, and;

Figure 7 a perspective view of this modified construction in its lay-flat condition or as coming from the mould.

Referring to the construction in further detail and wherein like reference characters designate corresponding parts in the different views, the sandal consists of a sole

portion 9 of suitable pliable material, preferably rubber, and having a heel portion 10. The sole and heel portions may be of uniform thickness throughout or the heel portion 10 ⁵ may be of greater thickness than the sole proper if preferred. Suitable means are provided for securely holding the sandal to the foot of the wearer at the toe, instep, and ankle thereof, and said attaching devices are ¹⁰ preferably formed integral with the sole of the sandal as a unitary structure and all in one and the same moulding operation.

The toe attaching device comprises a pocket-like portion 11 having apertures 12 and ¹⁵ 13 at the sides and extreme front. This construction of the toe engaging portion gives in effect the usual crossing toe straps characterizing the ordinary household sandal.

A pair of instep straps 14 are formed ²⁰ integral and continuous with the sole portion 9 as clearly shown in Figure 2 and the free ends of said straps are apertured as at 15 to receive the detachable button 16 for adjustably holding the straps across the ²⁵ instep of the wearer. Instead of the button member 16 any other suitable form of adjustable securing means may be employed. And instead of moulding said instep straps ³⁰ 14 as two separate members the invention contemplates moulding the same as one continuous piece adapted to be severed after the moulding operation as will be understood.

A heel piece 16^a has a bifurcated connection 17 at the extreme end of the heel portion 10 and at its upper end said member 16^a has a transversely extending and continuous member providing a pair of straps 18 of suitable length for encircling the ankle of the wearer. Apertures 19 are formed in each of ⁴⁰ the ankle straps 18 to receive the adjustable fastening means 20 as with the instep strap 14.

In its application to the foot of the wearer the two strap portions 14 are adapted to be ⁴⁵ selectively fastened in either of the positions illustrated in Figures 3, 4 or 5, accordingly as the wearer desires to have the "Grecian", "Swimmer" or "Roman" style. And it will be further understood that both ⁵⁰ of the strap members 14 may be secured across the instep of the foot if so desired.

In conformity with the foregoing the "Grecian" style of sandal is obtained by having the two foremost strap portions 14 ⁵⁵ extend to the toe portion 11 where they are secured to the same button 21 or other fastening device. In this instance the other pair of straps are brought across the instep and connected by the button member 16. In the ⁶⁰ "Swimmer" style the foremost straps are connected as in the "Grecian" style (Figure 3) and the rearmost straps 14 are connected to the button 22 on the heel strap 16^a located at the rear of the ankle. In the "Roman" ⁶⁵ style the foremost straps 14 pass over the

instep and the two rear straps are secured to the button 22 on the ankle strap 18 as shown.

It will therefore be seen that the bathing sandal herein disclosed is made up of the ⁷⁰ minimum amount of material, is produced and sold in its lay-flat form, has the least possible weight on the foot of the wearer, and thereby contributes to giving maximum comfort during walking or swimming. The ⁷⁵ sandal will remain firmly on the foot without discomfort from perspiration, and due to the novel form of foot attaching means there is ample ventilation entirely around the foot, and while swimming there is the least possible hindrance to action inasmuch as there is a complete avoidance of water pockets but on the other hand effective shedding of water.

It will be understood, of course, that in all ⁸⁰ places on the sandal or its attaching means where there is an appreciable fold-over or bend in the material that the moulding element thereat will obviate any liability of ⁸⁵ break or rupture in the texture or body of the ⁹⁰ rubber or other material.

Referring to Figures 6 and 7. The construction of sandal is in all essentials the same as above described, except that in this instance there is only one instep strap 23 instead of the pair of instep straps 14 in the other arrangement. It will be understood, of course, that when this style of sandal is used the two straps 23 fit about the instep of the foot in the ordinary way.

In the processes of moulding both the forms of sandal shown the instep strap portions (14 and 23) are formed in the lay-flat condition as illustrated. That is to say, said instep straps in the process of moulding lay ¹⁰⁰ within the plane of the sole and heel portion of the sandal. Also the ankle engaging strap 18 is formed in a lay-flat position with the heel portions (16 and 17) in the folded over arrangement as indicated in Figures 2 and 7. ¹⁰⁵

It will be understood that the invention as herein disclosed is not limited to the details of construction shown and described as these may be varied without departing from the spirit of the invention as defined by the ¹¹⁰ claims.

What is claimed as new is:

1. A sandal comprising a sole portion, a toe engaging portion, and an instep strap integral with the sole portion adapted to be attached to said toe engaging portion, substantially as set forth.

2. A sandal comprising a sole portion, an ankle engaging portion, and an instep strap integral with the sole portion adapted to be attached to said ankle engaging portion, substantially as set forth.

3. A sandal comprising a sole portion, toe and ankle engaging portions, and intermediate strap members integral with the sole por-

tion adapted to engage with said toe and ankle portions, substantially as set forth.

4. A sandal comprising a sole portion, toe and ankle engaging portions, and instep engaging strap members integral with the sole portion adapted to be connected with said toe and ankle engaging portions, substantially as set forth.

10 5. A sandal comprising a sole portion, toe and ankle engaging portions, and intermediate strap members integral with the sole portion adapted to engage the instep, or said instep and either the toe or ankle engaging portions, substantially as set forth.

15 6. A sandal comprising a sole portion, toe and ankle engaging portions, and intermediate strap members integral with the sole portion, said straps adapted to selectively engage either the instep only, or the toe and 20 ankle portions; or the instep and toe portion, or the instep and ankle portion, substantially as set forth.

25 7. The combination with a sandal having a sole portion, and toe and ankle engaging strap portions, of intermediate strap portions integral with the sole portion and adapted to selectively engage either the instep, or said toe and ankle engaging strap portions, substantially as set forth.

30 8. The combination with a sandal having a sole portion, and toe and ankle engaging strap portions, of intermediate strap portions integral with the sole portion and adapted to selectively engage either the instep, or the instep and either of the aforesaid engaging portions, substantially as set forth.

35 9. A bathing sandal constructed of rubber and as a single unit comprising a sole portion, toe and ankle engaging portions, and instep engaging portions; said instep engaging portions being integral with the sole portion and adapted to connect with either or both the toe and ankle engaging portions, substantially as set forth.

40 45 10. A bathing sandal constructed of rubber and as a single unit comprising a sole portion, a toe engaging pocket, an ankle strap, and a pair of instep engaging straps; said instep straps being integral with the sole portion and adapted to connect with either or both the toe engaging pocket and the ankle strap, substantially as set forth.

45 50 55 In witness whereof, I have hereunto set my hand at New York city, New York, this 22d day of March, A. D. nineteen hundred and twenty-nine.

LOUIS AUSTER.
